HANDRAIL AND REED HOLDER

Albert A. Gordon, 3rd, Worcester, Mass., assignor
to Crompton & Knowles Loom Works, Worcester, Mass., a corporation of Massachusetts

Application October 17, 1946, Serial No. 703,811

5 Claims. (Cl. 139—188)

1

This invention relates to improvements in hand rails and reed holders for looms and it is the general object of the invention to provide a hand rail and reed holder so made that it has negligible vibration during loom operation.

During the operation of a loom the lay swings backwardly and forwardly by power derived from the crank shaft and when it reaches approximately its mid position on its backward stroke the shuttle is picked. The power for picking the shuttle imposes a load on the loom driving motor which causes a temporary drop in the rate of motion of the lay. The shuttle is picked out of a shuttle box having a binder or shuttle check exerting a holding force on the shuttle, and when this holding force is overcome as the shuttle is moved out of the box there is an endwise thrust imparted to the lay. The reed along which the shuttle travels is held along its lower edge by a part of the lay and along its upper edge by a hand rail.

When looms are operated at high speed and hand rails are made as constructed heretofore, that is, of wood or combinations of wood and steel, the temporary interruption in the backward motion of the lay and the aforesaid end thrust incident to picking set up vibrations in the hand rail which cause back and forth movements of the upper end of the reed with respect to the lay. This movement of the reed interferes with the flight of the shuttle because of the fact that the reed does not present a straight line guide for the shuttle.

I have found that when the hand rail is made of a light metal or alloy the principal component of which is either magnesium or aluminum the hand rail vibration is very slight and the reed is therefore held with its upper end in practically a straight line. The shuttle is thus guided in a straight path along the lay and can be picked more smoothly out of and into shuttle boxes.

Hand rails generally are provided with a groove to receive the upper end of the reed and are customarily provided with some form of shuttle guard usually fastened by screws or bolts to the wooden part of the hand rail. It is another object of my present invention to provide a hand rail made in one piece of the metals already mentioned and having a reed receiving groove on the bottom of a rear vertical web, a horizontal forwardly extending top web, and a depending front apron or the like serving as a shuttle guard. The two webs and apron are integral and provide a stiff but lightweight hand rail which possesses the advantages already mentioned.

2

With these and other objects in view which will appear as the description proceeds, my invention resides in the combination and arrangement of parts hereinafter described and set forth.

In the accompanying drawings, wherein a convenient embodiment of my invention is set forth,

Fig. 1 is a side elevation of part of a loom having the lay thereof provided with my improved form of hand rail and reed holder,

Fig. 2 is an enlarged front elevation looking to the direction of arrow 2, Fig. 1,

Fig. 3 is an enlarged plan view of one end of the hand rail looking in the direction of arrow 3, Fig. 2,

Figs. 4 and 5 are vertical sections on lines 4—4 and 5—5, respectively, of Fig. 2, and

Fig. 6 is a perspective view of one end of the hand rail viewed from the rear thereof.

Referring to Fig. 1, the loom frame 10 is provided with top and bottom shafts 11 and 12 connected together by the usual gearing 13. The top or crank shaft has a connector 14 attached as at 15 to a lay 16 mounted on lay swords one of which is shown at 17. The lay swords move about an axis relatively low in the loom, the axis for the swords shown in Fig. 1 being defined by a rocker shaft 18 which is fixed with respect to the loom frame. As shaft 11 rotates the lay moves back and forth in the usual manner. The lay is provided with a shuttle box 20 to receive the shuttle S, and the latter when boxed lies between a box back 21 fixed to the lay and some form of check, such as the usual binder 22. A picker stick P picks the shuttle out of box 20 during rearward movement of the lay.

The warp W, supplied in usual manner, extends forwardly through a reed R having top and bottom rails 25 and 26 between which extend the reed dents 27. The lay swords have upward extensions 28 one of which is shown particularly in Fig. 4. The bottom rail 26 is held on the lay by the usual backstay 29.

When the picker stick exerts end force on the shuttle S as the lay reaches approximately the mid position of its backward stroke there is a temporary drop in loom speed, and the lay instead of moving rearwardly with a smooth motion is subject to a slight interruption. This interruption occurs at the same time the picker stick pushes the shuttle S out of the shuttle box 20 against the frictional forces exerted by the box back 21 and the binder 22. As the shuttle leaves the box it is guided through the warp shed

along the reed R and ultimately reaches another shuttle box at the opposite side of the loom. At the instant of picking, therefore, the lay is subject to forces tending to set up vibrations in the reed, and it is obvious that the rigidity of the reed with respect to the lay will have an important bearing on the character of motion of the shuttle.

In carrying my present invention into effect I provide a hand rail and reed holder designated generally at H having a rear vertical web 30, a top forwardly extending web 31, and a depending shuttle guard apron 32. The two webs and apron are formed integral with each other and extend lengthwise across the lay. The bottom of the rear web 30 is forked to provide front and back walls 33 and 34, respectively, defining a downwardly opening groove 35 which receives the upper reed rail 25. As shown in the drawings the rear wall 34 is curved backwardly so that the lower end thereof is behind the upper rear part of web 30, but this is not an essential feature of the hand rail.

In order to receive the lay sword arms 28 the vertical web 30 at the rear of each end thereof is provided with a flat surface 36 which extends vertically downwardly from the top web 31 along the rear part of the vertical web 30 and cuts across the rear part of the rear wall 34 as shown in Fig. 6 to define a shoulder 37 which fits closely against the adjacent lay sword extension 28. An aperture 38 extends through the web 30 and surface 36 below the top web 31 and above the front wall 33. Aperture 38 receives a bolt 39 having a head 40 which is drawn against an elongated washer 41 when a wing nut 42 is tightened. The washer 41 is preferably though not necessarily made of the same material as that of which member H is made, and fits snugly between the top web 31 and wall 33 and is thus held against turning.

The previously mentioned apron 32 hangs downwardly substantially parallel to the rear web 30 and forms a shuttle guard which may be of any desired depth. Because of the construction of the member H sufficient rigidity can be attained by having a relatively shallow apron 32 and this permits a considerable amount of light to fall on the fell of the cloth. This is of particular advantage when center filling stop motions are used.

A loom equipped with a hand rail and reed holder as set forth hereinbefore shows in actual practice that there is practically no back and forth vibration of the member H during loom operation. The hand rail is light and when made of magnesium or aluminum, or alloys made principally of these metals, the reed remains substantially straight and affords a straight guide for the back wall of the shuttle. Tests made by sensitive instruments adapted to measure very small deflections show that the usual hand rail is subject to considerable vibration as already mentioned, but when the hand rail is made as set forth herein the curve representing its deflections is to all intents and purposes a straight line.

While the hand rail has been described as being made of magnesium or aluminum, in actual practice an alloy of one or another of these metals is used. Thus, in one instance, I have made the hand rail of an extruded alloy of magnesium containing 1.5% manganese. It is not known just which property of these metals is responsible for the vibration dampening effect, but I believe their specific gravities and also their moduli of elasticity

are closely associated with the advantages already mentioned. At room temperature the specific gravity of magnesium can be taken as 1.74, while that of aluminum is 2.80. It may be that such alloys as are suitable for hand rails will vary slightly from these figures, but the range of specific gravity of the metal of which the hand rail is made will be substantially from 1.74 to 2.80. The modulus of elasticity is approximately 6,000,000 for magnesium and 10,000,000 for aluminum, and there may be slight variations in these figures for alloys of these two metals. Wood such as has been used for hand rails heretofore has a range of modulus of elasticity of 1,285,000 for white ash native to New England to 1,485,000 for western grown ash. The modulus of elasticity of the steel when used as a reinforcement for the wood is from 28,000,000 to 29,000,000. The specific gravity of the wood is from .5 to .6, while the specific gravity of the reinforcing steel is from 7.7 to 7.83. It will therefore be seen that the metals mentioned herein lie intermediate wood and steel so far as the ranges of their specific gravity and moduli of elasticity are concerned.

From the foregoing it will be seen that I have provided an improved form of hand rail and reed holder made of magnesium or aluminum, or alloys formed principally of these metals, and that the hand rail because of the material of which it is made damps vibrations to such an extent that the top of the reed is prevented from vibrating back and forth and the shuttle is for all practical purposes guided in a straight line across the lay. It will also be seen that the shuttle guard is integral with the hand rail and together with the rear and top webs 30 and 31 provides a reed holder possessed of considerable rigidity. The apron 32 forming the shuttle guard is so constructed as to permit a considerable amount of light to fall on the fell of the cloth when the lay is in forward position, thereby facilitating an examination of the weft when the loom is stopped by a center stop motion. Shoulder 37 abuts lay sword extension 28 and assists in holding the member H firmly in position.

Having thus described my invention it will be seen that changes and modifications may be made therein by those skilled in the art without departing from the spirit and scope of the invention and I do not wish to be limited to the details herein disclosed, but what I claim is:

1. A combined hand rail and reed holder for a loom lay having lay swords, said rail and holder being an elongated member having a vertical web the lower end of which is divided to form front and back walls defining a reed receiving groove, the rear wall extending behind said web and the ends of the member being provided with flat rear surfaces for attachment to the lay swords, said rear wall having a shoulder adjustment to the associated flat surface to engage the corresponding lay sword.

2. A combined hand rail, reed holder and shuttle guard for a loom lay comprising an elongated one-piece member having a rear vertical web the lower edge of which is formed with a longitudinal reed receiving groove, a top web extending forwardly from the top of said rear web, and an apron depending from the front of the top web and forming a shuttle guard.

3. A combined hand rail, reed holder and shuttle guard for a loom lay comprising an elongated member having a rear vertical web the lower edge of which is formed with a longitudinal reed receiving groove, a top web extending forwardly

from the top of said rear web, and an apron depending from the top web forward of and parallel to the rear web and forming a shuttle guard, said webs and apron being integral throughout the length of said member.

4. In a combined hand rail and reed holder for a loom lay having lay swords, said rail and holder comprising an elongated member having a rear web the lower edge of which is divided to form front and back walls defining a longitudinal groove to receive part of a reed, a top web extending lengthwise of said member and projecting forwardly from the upper part of said rear web, said front wall projecting forwardly from the rear web and extending lengthwise of said member, and means securing said member to said lay sword including an elongated washer in front of said rear web and between said top web and front wall.

5. A combined hand rail and reed holder for a loom lay comprising an elongated member having a vertical web the lower edge of which is forked to form front and back horizontally spaced longitudinally extending walls between

which is located a reed receiving groove, said front wall extending forwardly from said rear web, and a top web integral with the rear web extending forwardly from the upper part of the rear web and overhanging said front wall.
